UNITED STATES PATENT OFFICE.

CHARLES S. DU BELLE, OF WILLIAMSPORT, PENNSYLVANIA.

HAND STAMP MACHINE.

Application filed March 20, 1925. Serial No. 17,070.

This invention relates to hand stamp machines, and has for its object to provide simple and efficient means for applying ink to the type or printing wheels of such machines, together with means for maintaining a constant supply of ink and distributing the same upon the surface of an inking roller in such manner as to insure an even distribution and prevent over-saturation.

10 A further object is to provide simple and efficient means for throwing the inking roller out of position to contact with the face of the type or printing wheels, together with means for securing it in such position, or in contacting position, as desired, during the stamping operation.

The invention will first be hereinafter more particularly described with reference to the accompanying drawings, which are to be 20 taken as a part of this specification, and then pointed out in the claims at the end of the description.

In said drawings, Fig. 1 is a side elevation of a dating machine embodying my invention, showing the oscillating frame of the inking device in raised position;

Fig. 2 is a rear elevation of said machine with said oscillating frame in the position shown in Fig. 1;

30 Fig. 3 is a side elevation of said machine with said oscillating frame in the same position as that shown in Figs. 1 and 2;

Fig. 4 is a vertical sectional elevation showing said oscillating frame in its lowermost 35 position with the inking roller out of contact with the face of the type or printing wheels;

Fig. 5 is a detail sectional view of the fluid inking reservoir detached;

Fig. 6 is a transverse section of said reservoir;

Figs. 7 and 8 are detail perspective views of parts of the means employed for throwing the inking roller out of contact with the type or printing wheels; and

45 Fig. 9 is a detail of a lever locking pawl or dog.

In the illustrated embodiment of my invention, I have shown the same applied to a dating machine, but it is adapted for general 50 application to machines of different types,

its application to a dating machine being merely illustrative of a particular type of machine with which it is designed to be used, as the invention may be applied to various kinds of machines, for example, numbering 55 machines, check writing machines, printing presses, and the like.

The machine shown has mounted on its supporting frame a reciprocating plunger provided with a suitable handle, and carrying a printing wheel frame which is vertically movable therewith and in which are revolvably supported printing wheels of ordinary construction, with the usual means for operating the same, all of which parts are of known construction and need not be specifically described.

In said drawings, in which the same reference letters are used to denote corresponding parts in different views, the letter A denotes the main supporting frame, B the plunger and C the printing wheel frame, over which I preferably place a shield D, having front and rear apron-like members, for a purpose hereinafter mentioned.

70 The inner sides or confronting surfaces of the legs of the supporting frame have vertical grooves therein to receive projections or studs e on the printing wheel frame which protrude through openings in side plates of an oscillating frame E which carries the fluid inking reservoir F, also a roller G, for spreading the ink evenly on the periphery of the inking reservoir, and an inking or ink delivering roller I; said reservoir being adapted to distribute ink upon the spreading roller, which in turn delivers ink to the inking roller.

75 Said side plates have pivoted thereto on the inner sides thereof oscillatory or swinging levers H, of the form shown in Fig. 7, in which the shafts of the spreading and inking rollers have their bearings; the ends of said shafts protruding through slightly elongated openings G¹ and I¹, respectively in said side plates.

90 The spreading roller is in peripheral contact with said inking roller and with the distributing or feeding surface of the fluid inking reservoir. The spreading roller is of 95 felt or other soft and absorbent material 100

while the inking roller is preferably of rubber.

The levers H are pivotally supported on the inner sides of the side plates of the oscillating frame E, and are each forked or bifurcated at the outer end while the other ends thereof carry inwardly projecting studs or pins h to each of which is secured one end of a coiled or other suitable spring h¹, the other end of which is secured to a transverse rod or bar h² connecting the side plates of the oscillating frame at the lower ends thereof, so as to adapt said springs to actuate the swinging levers so as to hold the inking roller normally in position to contact with the face of the type or printing wheels when lowered by the oscillating frame into contacting position, and hold it in such position until thrown out of normal position by cam-actuated means carried by the oscillating frame and engaging the forked ends of said swinging levers; said means comprising a rod M fitted in alined openings in the side plates of the oscillating frame E and provided at one end with an operating lever m and having fixed thereon eccentric disks or cams m¹ which are fitted in the forks or bifurcated ends of the swinging levers so that when the cam-carrying rod M is turned in one direction said cams will actuate said swinging levers so as to throw the inking roller into position to prevent contact thereof with the face of the type or printing wheels when the oscillating frame is lowered and hold it in such position. On the reverse movement of said cam-carrying rod, the inking roller will be thrown into position to contact with the face of the type or registering wheels when the oscillating frame is lowered and maintained in such position until the cam-carrying rod is again rotated to throw the inking roller out of contacting position.

The operating handle m has its free end turned inwardly as at m² to engage alternately depressions m³ and m⁴ on the outer side of the adjacent side plate of the oscillating frame E, so as to hold the inking roller in either contacting or non-contacting position.

The side plates of the oscillating frame are eccentrically fulcrumed upon the legs a of the supporting frame A by means of a shifting fulcrum consisting of pins or screws e screwed into interiorly threaded openings therefor in said legs and protruding into elongated slots e¹ in said side plates, so that when the plunger is lowered its downward movement with the studs c along the vertical grooves in the supporting frame will rock the oscillating frame upon its fulcrum or pivots e and raise the free end thereof, thus causing relative movement of said fulcrum or pivot pins along the slots e¹ so as to permit the oscillating frame to be raised into the position shown in Fig. 1 of the drawings,

thereby raising the fluid inking reservoir and throwing the inking roller out of contact with the face of the type or printing wheels.

The inking reservoir F is preferably composed of telescopically connected inner and outer tubular members f and f¹, but they may be polygonal in cross-section, and each is open at one end and closed at the other end, said closed end of one or both members having a filling aperture therein which is provided with a removable stopper f² for closing said filling aperture. Each member has minute orifices or pin-holes therein arranged normally in separated relation but adapted to be brought into registering position by adjusting or moving one of said members in the line of its axis. Each tubular member of the inking reservoir is provided at the closed end thereof with a radially projecting flange f³, which is preferably annular in form and between said flanges is secured a cylindrical body F¹ of felt or other absorbent material surrounding the reservoir, said body being preferably composed of a series of rings arranged side by side and having annular metal plates f⁴ on the outer sides of the outer rings connected by a bolt or bolts f⁵ passing through the series of rings and securing them together so that they will rotate in unison.

To prevent rotary movement of the cylindrical body or feeder independently of the tubular members of the ink reservoir a nail or other fastening device f⁶ is inserted through the flange f³ on the outer member and through the adjacent plate f⁴ into said body.

To rotate the ink reservoir the closed end of the outer member thereof may be formed with a reduced end portion on which is fixed a gear wheel N beside which is a ratchet wheel n secured thereto and to the outer member of the ink reservoir by means of a screw n¹ so as to cause said parts to rotate in unison; the screw n¹ being concealed and held in place behind a flange on the end of the stopper f². The pinion N¹ is fixed on one end of the spreading roll shaft and meshes with the gear wheel N and with a gear wheel O on one end of the shaft of the inking roller I so that when rotary movement is imparted to the gear wheel N and through it to the ink reservoir and feeder, the spreading roll will be caused to rotate in an opposite direction while the inking roller rotates in the same direction.

Rotary movement is imparted to the described train of gears by means of a pawl P pivoted at one end on the supporting frame A and having a tooth on the other end adapted to engage the teeth of the ratchet wheel n and rotate the gear wheel N and through it the inking and spreading rollers when the free end of the oscillating frame moves downwardly, said frame being adapted to swing

along curved lines eccentric to the pivot of the pawl P, and on the reverse movement said pawl will slide freely over the inclined teeth of the ratchet for engagement with another tooth on the next downward movement of the oscillating frame.

Means are provided at one end of the inking reservoir for adjusting and securing the fluid containing member f with the orifices 10 therein in registering position with the orifices in the outer member f¹ and vice versa, such means, in the form shown, consisting of a lever R pivoted intermediate its ends to a lug or bracket on the outer side of the 15 adjacent side plate of the oscillating frame and having a forked end engaging a groove r in a hub-like end portion of the inner member of the inking reservoir; a coiled or other suitable spring S being secured between the 20 side plate of the oscillating frame and the free end of the lever R so as to normally force said free end outwardly and hold the inner fluid containing member of the reservoir with its orifices in separated relation to the orifices 25 in the outer member f¹.

Pressure upon the free end of the lever R against the force of the spring S will move said fluid containing member in the direction of its axis so as to cause the orifices therein to register with the orifices in the outer member and the lever may be locked in such position by means of a pawl or dog T pivoted at one end on the outer side of the adjacent side plate of the oscillating frame and having 30 a hook on its free end adapted to take over the free end of the lever and hold it in a fixed position against the pressure of the spring S.

To prevent rotation of the outer member of the inking reservoir independently of the 40 inner member, the outer member has formed therein an open-ended slot f¹; Fig. 5, in which is fitted a stud or projection on the outer side of the inner member; which compels the two members to rotate together.

45 The shield D is of substantially U-shaped form, with its top resting on the top of the printing wheel frame so that its depending apron-like portions will prevent the printing wheels from being exposed at the front and rear of the machine; the front apron-like portion being provided with a vertical elongated slot therein through which protrudes a lever V operatively connected with the printing wheels by any suitable means for imparting 50 rotary movement thereto, step by step, in a manner well known in this class of machines. While desirable to use said shield it may be omitted.

60 The holes in the side plates of the oscillating frame through which the ends of the shafts of the inking and spreading rollers protrude, are slightly elongated, as shown in Fig. 1, so as to permit said rollers to move slightly sidewise when the swinging lever m 65 is moved from the position shown in Fig. 1

into engagement with the depressions m⁴. The pivoted end of the pawl or dog T is of elbow-shaped form to adapt it to be locked in either an upright position, out of engagement with the lever R, as shown in Figs. 5 70 and 9, or in a horizontal position, in engagement with said lever, by means of a spring W secured at one end to the side plate which carries said pawl and having its free end arranged to bear normally upon the back of the pawl and hold it out of engagement with the lever, so as to allow the spring S to hold the inner member of the ink reservoir with its 75 apertures out of position to register with the apertures in the outer member, but when the pawl is thrown into engagement with the lever the free end of the spring will bear upon the pivoted end of the pawl, past a dead center, and lock the pawl in engagement with the lever so as to hold the two members of 80 the ink reservoir with the orifices therein in registering position until the lever is released.

In operation, the spreading roller being in contact with the inking roller and with the ink reservoir or the cylindrical body of absorbent material surrounding said reservoir, when the plunger is depressed it will cause the oscillating frame to swing downwardly, carrying the inking roller into contact with and past the face of the type of the printing 90 wheel or wheels, and at the same time imparting a slight rotary movement thereto and to the spreading roller and ink reservoir, thus causing the latter roller to spread the ink evenly on or over the periphery of the 95 ink reservoir, and when the plunger is raised, by spring pressure acting thereon in the usual manner, to effect the return movement, the inking roller will contact with the type face in a freshly inked place thereon, thus 100 leaving the type cleanly and smoothly inked.

It will be understood of course that various changes may be made in the details of construction and arrangement of parts without departing from the spirit and scope of 110 my invention. For example, it may be desirable in some cases to dispense with one of the rollers G or I and use only a single roller to carry ink from the ink reservoir to the type, such roller being made of suitable material for the purpose, and instead of a series of rings of absorbent material surrounding the fluid inking reservoir, I may use a solid cylindrical body of such material, and the two members of the fluid reservoir may be 115 of polygonal form in cross-section, thus adapting them to rotate together without extraneous fastening means, and I therefore do not desire to limit my invention as defined in the appended claims to the specific construction shown and described or to the particular material specified, and I also desire it to be understood that the expression "hand stamp machine" is intended to include various kinds of machines to which my inven- 120 125 130

tion may be applied, as hereinbefore stated, and that the word "tubular" as used in the appended claims is intended to include polygonal or other forms, while the expression 5 "cylindrical body of absorbent material" is intended to include either a solid body or a series of rings, such as shown and described.

Having thus described my invention, what I claim as new and desire to secure by Letters 10 Patent of the United States is:

1. A fluid inking reservoir comprising two concentric cylindrical members one slidably fitted within the other, each open at one end and closed at the other end and having minute 15 orifices therein normally separated but adapted to be brought into registering position, the open end of the inner member facing the closed end of the outer member and one of said closed ends having a filling aperture therein 20 provided with a removable stopper each of said cylindrical members having a radially projecting flange at its closed end, a cylindrical body of absorbent material surrounding the outer member and relatively stationarily 25 confined between said flanges, and means for moving one of said members in the direction of its axis so as to cause the orifices therein to register with the orifices in the other member.

30 2. A fluid inking reservoir comprising two concentric cylindrical members one slidably fitted within the other, each open at one end and closed at the other end and having minute 35 orifices therein normally separated but adapted to be brought into registering position, the open end of the inner member facing the closed end of the outer member and one of said closed ends having a filling aperture therein provided with a removable stopper each of said cylindrical members having a radially projecting flange at its closed end, a cylindrical body of absorbent material surrounding the outer member and relatively 40 stationarily confined between said flanges and means for moving one of said members in the direction of its axis so as to cause the orifices therein to register with the orifices in the other member, together with means for holding 45 said members with the orifices therein in either registering or non-registering position.

50 3. A fluid inking reservoir and feeder for the inking rollers of hand stamping machines, comprising a fluid containing member of tubular form slidably fitted within a similar tubular member each open at one end and closed at the other end and each having minute 55 orifices therein spaced apart longitudinally thereof and normally separated but adapted to be brought into registering position, the open end of the inner member facing the closed end of the outer member, and one member having a filling aperture therein provided with a removable stopper, a cylindrical body of absorbent material surrounding said members, a spreading roller in contact with said 60

cylindrical body, an inking roller in contact with said spreading roller, and means for yieldingly holding said members with the orifices therein in non-registering position, together with means for moving one of said members back and forth in the direction of its axis so as to cause the orifices therein to register with the orifices in the other member. 70

4. A fluid inking reservoir and feeder for the inking rollers of hand stamping machines, 75 comprising a fluid containing member of tubular form slidably fitted within a similar tubular member each open at one end and closed at the other end and each having minute orifices therein normally separated but adapted to be brought into registering position, the open end of the inner member facing the closed end of the outer member and one member having a filling aperture therein provided with a removable stopper, a cylindrical body of absorbent material surrounding said members, a spreading roller in contact with said cylindrical body, an inking roller in contact with said spreading roller, and means for yieldingly holding said members with the orifices therein out of registering position, together with means for moving one of said members in the direction of its axis, so as to cause the orifices therein to register with the orifices in the other member, together with releasable means for locking said members with the orifices therein in registering position. 85

5. A fluid inking reservoir for hand stamping machines comprising telescopically connected members of tubular form each having minute orifices therein normally separated but adapted to be brought into registering position and each open at one end and closed at the other end and having at its closed end a radially projecting flange, and a series of rings of absorbent material surrounding the outer member and non-rotatively confined between said flanges, the closed ends of said members each having a filling aperture therein and removable stoppers for closing said apertures. 100

6. A fluid inking reservoir for hand stamping machines comprising telescopically connected members of tubular form each having minute orifices therein normally separated but adapted to be brought into registering position and each open at one end and closed at the other end and having at its closed end a radially projecting flange, and a series of 105 rings of absorbent material surrounding the outer member and non-rotatively confined between said flanges. 110

7. A fluid inking reservoir for hand stamping machines, comprising telescopically connected members of tubular form each having minute orifices therein normally separated but adapted to be brought into registering position and each open at one end and closed at the other end and having at its closed end a 115

120

125

130

radially projecting flange, a series of rings of absorbent material surrounding the outer member and non-rotatively confined between said flanges, and manually operated means 5 for effecting movement of one of said members in the direction of its axis so as to cause the orifices therein to register with the orifices in the other member.

8. A fluid inking reservoir for machines of 10 the character described comprising telescopically connected members of tubular form each having minute orifices therein normally separated from but adapted to be brought into registering position with the orifices in the 15 other member and each open at one end and closed at the other end and having at its closed end a radially projecting flange, a series of rings of absorbent material surrounding the outer member and non-rotatively confined between 20 said flanges, and manually operated means for adjusting one of said members in the direction of its axis, said means comprising a lever fulcrumed on a fixed support at one end of said reservoir and engaging a groove in 25 a projecting end-portion of one of said members, and a spring acting on said lever tending to hold said members in relatively fixed positions with the apertures therein out of registering position.

30 9. An inking device for hand stamp machines, comprising a series of rings of absorbent material surrounding a fluid container consisting of inner and outer telescopically connected members of tubular form each having 35 minute orifices therein, a spreading roller in contact with the periphery of said body, an inking roller in contact with the periphery of said spreading roller, means for holding said members with their respective orifices 40 normally in separated relation, and means for moving one of said members in the direction of its axis so as to cause the orifices therein to register with the orifices in the other member; said container having a filling aperture provided with a removable stopper, and means for securing said rings together and to the container so as to prevent rotation of one independently of the other.

50 10. An inking device for hand stamp machines, comprising a cylindrical body of absorbent material surrounding a fluid container consisting of inner and outer telescopically connected members of tubular form each having minute orifices therein, a spreading 55 roller in contact with the periphery of said body, an inking roller in contact with the periphery of said spreading roller, means for holding said members with their respective orifices normally in separated relation, means 60 for moving one of said members in the direction of its axis so as to cause the orifices therein to register with the orifices in the other member, and releasable means for securing the movable member with its orifices in registering position together with spring-actuated

means for yieldingly holding said members with the orifices therein out of registering position, said container having a filling aperture provided with a removable stopper.

11. The combination, in a machine of the 70 character described, of a supporting frame having mounted thereon a reciprocating plunger carrying printing devices, a roller for applying ink to said devices, and means for supplying ink to said roller; said means 75 comprising a revoluble container consisting of hollow telescopically connected members each having minute orifices therein spaced apart longitudinally thereof; one member being movable relatively to the other member, so as to cause the orifices therein to register with the orifices in the other member, or move them into non-registering position, 80 a solid comparatively thick body of absorbent material surrounding said container and revoluble therewith, and means for adjusting said movable member and holding it relatively stationary with the orifices in the two members in either registering position or in separated relation, together with means actuated by the movements of said plunger 85 for moving said printing devices and said roller alternately into and out of ink-applying position.

12. In a machine of the character described, 90 a supporting frame having mounted thereon a reciprocating plunger carrying type or printing wheels, a fluid inking reservoir comprising a revoluble container consisting of hollow telescopically connected members 100 each having minute orifices therein spaced apart longitudinally thereof and normally out of registering position with the orifices in the other member, a solid body of absorbent material surrounding said container 105 and revoluble therewith; one of said members being movable relatively to the other member in the direction of its axis, so as to cause the orifices therein to register with the orifices in the other member, and means 110 for holding said members relatively stationary with the orifices therein in either registering or non-registering position, together with means for receiving ink from said reservoir and applying it to said type or printing wheels, and means actuated by the movements of said plunger for moving said type or printing wheels and said ink receiving and applying means alternately into and out of ink-applying position.

13. A fluid inking reservoir for hand stamping machines, comprising telescopically connected members of tubular form, each having minute orifices therein spaced apart longitudinally thereof and normally separated but adapted to be brought into registering position by longitudinal movement of one member upon or within the other and each open at one end and closed at the other end and having at its closed end a radial- 130

ly projecting flange, and a cylindrical body of absorbent material surrounding the outer member and secured thereto between said flanges, so as to prevent rotation thereof 5 independently of said outer member.

14. A fluid inking reservoir for hand stamping machines comprising telescopically connected members of tubular form each having minute orifices therein normally separated but adapted to be brought into registering position and each open at one end and closed at the other end and having at its closed end a radially projecting flange, a cylindrical body of absorbent material surrounding the outer member between said flanges and means to prevent rotation of said body independently of said outer member; one of said members having a filling aperture therein provided with a removable 20 stopper.

15. A fluid inking reservoir for hand stamping machines, comprising concentric telescopically connected cylindrical members each having minute orifices therein normally separated but adapted to be brought into registering position and each open at one end and closed at the other end and having at its closed end a radially projecting flange, a cylindrical body of absorbent material surrounding the outer member and relatively 30 stationarily confined thereon between said flanges, and manually operable means for effecting movement of one of said members in the direction of its axis so as to cause the orifices therein to register with the orifices in the other member.

16. A fluid inking reservoir for machines of the character described comprising concentric telescopically connected members of tubular form each having minute orifices therein normally separated but adapted to be brought into registering position with the orifices in the other member and each open at one end and closed at the other end and having at its closed end a radially projecting flange, a cylindrical body of absorbent material surrounding the outer member and relatively stationarily confined thereon between said flanges, one of said members having a filling aperture therein provided with a removable stopper, and manually operable means for adjusting one of said members in the direction of its axis, said means comprising a lever fulcrumed on a fixed support at one end of said reservoir and engaging a groove in a projecting end-portion of one of said members, and a spring acting on said lever for yieldingly holding said members in relatively fixed positions with the apertures 55 therein out of registering position.

17. In a device of the character described, a fluid inking reservoir comprising hollow inner and outer telescopically connected members each having minute orifices therein spaced apart longitudinally thereof and nor-

mally out of registering position with the orifices in the other member; one of said members being adjustable longitudinally of the other to bring said orifices into registering position, and a series of rings of absorbent 70 material surrounding said outer member and secured thereto so as to prevent rotation thereof independently of said outer member; one of said members being provided with a filling aperture.

18. In a device of the character described, a fluid inking reservoir comprising hollow inner and outer telescopically connected members each having minute orifices therein spaced apart longitudinally thereof and normally out of registering position with the orifices in the other member; one of said members being adjustable longitudinally of the other to bring said orifices into registering position, means for yieldingly holding said 80 members with said orifices out of registering position, and means for holding said members with the orifices in registering position; and a body of absorbent material surrounding said outer member and secured thereto so 90 as to prevent rotation thereof independently of said outer member; one of said members being provided with a filling aperture and a closure therefor.

19. The combination, in a machine of the 95 character described, of a supporting frame having mounted thereon a reciprocating plunger carrying printing devices, and an oscillating frame actuated by said plunger and carrying means for applying ink to said devices during the reciprocating movements of the plunger; said ink-applying means comprising a rotary ink-container consisting of hollow telescopically connected members each having minute orifices therein spaced 100 apart longitudinally thereof and normally out of registering position with the orifices in the other member, means for moving one of said members in the direction of its axis, so as to cause the orifices therein to register 105 with the orifices in the other member, together with means for holding said members relatively stationary with the orifices therein in either registering or non-registering position, a body of absorbent material encircling 110 said container, and means for imparting a slight rotary movement to said container during the reciprocating movements of the plunger.

20. The combination, in a machine of the 115 character described, of a supporting frame having mounted thereon a reciprocating plunger carrying printing devices, and an oscillating frame actuated by said plunger and carrying means for applying ink to said devices during the reciprocating movements of the plunger; said ink-applying means comprising a rotary ink-container consisting of hollow telescopically connected members each having minute orifices therein spaced apart 120

longitudinally thereof and normally out of registering position with the orifices in the other member, means for moving one of said members in the direction of its axis, so as to cause the orifices therein to register with the orifices in the other member, together with means for holding said members relatively

stationary with the orifices therein in either registering or non-registering position, and a body of absorbent material encircling said container. 10

In testimony whereof I affix my signature.

CHARLES S. DU BELLE.
